UNITED STATES PATENT OFFICE.

JOHN E. LOMBARD AND JOSEPH R. BOWLING, OF ST. LOUIS, MISSOURI,
ASSIGNORS TO THE INGOLDSBY AUTOMATIC CAR COMPANY, OF ST.
LOUIS, MISSOURI, A CORPORATION OF WEST VIRGINIA.

BOLSTER FOR RAILWAY-CARS.

SPECIFICATION forming part of Letters Patent No. 728,479, dated May 19, 1903.

Application filed August 27, 1902. Serial No. 121,155. (No model.)

To all whom it may concern:

Be it known that we, JOHN E. LOMBARD and JOSEPH R. BOWLING, citizens of the United States, residing at St. Louis, in the State of Missouri, have invented a certain new and useful Improvement in Bolsters for Railway-Cars, of which the following is a full, clear, and exact description, reference being had to the accompanying drawings.

- 10 • This invention relates to steel bolsters of the general type shown in Patent No. 694,385, granted March 4, 1902, to the Ingoldsby Automatic Car Co., as assignee of Frank S. Ingoldsby and Joseph R. Bowling.
- 15 15 The object of the present invention is to strengthen and stiffen such a bolster and at the same time rendering its construction simpler and cheaper.

The invention relates particularly to the construction at the outer ends of the bolster, as hereinafter fully explained.

In the drawings, Figure 1 is a side elevation of something over one-half the bolster sectioned through the contiguous portions of the car. Fig. 2 is an enlarged side elevation, partly broken away, of a portion of the bolster at the end thereof. Fig. 3 is an elevation of the end of the bolster. Fig. 4 is a plan view of the bolster near its end, and Fig. 5 is

30 a vertical section on the line 5 5 of Fig. 2.

In its complete form the bolster shown comprises a central frame A, a channel-shaped compression member B, extending beneath the frame and diagonally upward therefrom, a tension-strap C, extending over the top of the frame and secured at its ends to the compression member, tension-braces D, leading from the compression member to the central frame, compression-braces E and F, connecting the tension-strap with the compression member, and a suitable center bearing G and side bearings H, carried on the under side of the compression member.

When installed in the car, vertical draft-45 plates J preferably engage the sides of the central frame of the bolster and are riveted to it, and a longitudinal sheet K of inverted-V form lies between the central frame and the tension-strap, being secured to each of

them. Diagonal beams L from the end to the 50 sides of the car may extend through the compression-braces F. The side of the car which rests upon and is secured to the outer end of the bolster may have, as shown, a sheet-metal plate N, a channel-beam N', and an 55 inclined Z-strut N².

The above-described construction is shown and claimed partly in the patent to Ingoldsby and Bowling referred to and partly in an application of Ingoldsby and Bowling filed on 60 the 25th day of August, 1902, and numbered serially 120,922, and no claims are made herein for any such features.

The particular purpose of the present invention is to strengthen and stiffen the outer 65 ends of the bolster. The means by which we accomplish this will now be described.

Secured to the under side of the channel member B, at its outer end, is the angle-clip P. The tension-strap C is bent downward 70 at its outer end, as at c, where it is riveted to the angle-clip P by the rivets p. Between the tension-strap and the compression member is a filling-block Q. The tension-strap extends inward horizontally on top of the 75 filling-block, beyond which it inclines upward.

Extending over the top of the tension-strap C is a peculiarly-shaped stirrup R, which is secured to the tension-strap and to the compression member. This stirrup is formed of a sheet-metal plate, which is bifurcated on opposite sides by having pieces cut out of it at r, after which it is bent into the inverted-U shape or stirrup form, presenting a substantially horizontal top plate r' and an inclined top plate r² and vertically-depending plates r³ and r⁴, which are riveted to the flanges of the compression member at r⁵ and r⁶, respectively. Rivets r⁷ hold the inclined portion r² 80 of the plate to the tension-strap. Rivets r⁸ pass through the compression member, the filler-block, the tension-strap, the stirrup, and the flange of the channel-beam N'. A rivet r⁹ passes through the compression member, 85 the filler-block, the tension-strap, the stirrup, and an angle-clip N³, which is secured to the inclined Z-beam N². Another rivet¹¹ passes

through all these parts and also through the angle-clip P. Other rivets ^{r¹²} pass through the compression member, the filler-block, the tension-strap, and the stirrup.

5 The above specific description of the rivets shows how simple it is to construct this portion of the bolster, while at the same time the parts are very securely held. There are no 10 inaccessible places to rivet. The stirrup not only provides a reinforcing thickness for the tension-strap C, but a vertical depth for the whole end of the bolster, thereby greatly increasing its stiffness and strength. The openings r in the side plates of the stirrup allow 15 the stirrup to be very easily formed from a flat sheet-metal plate.

We claim—

1. In a bolster, the combination of a channel-shaped compression member, a tension-strap secured to the compression member near its end, and a sheet-metal stirrup extending over the tension-strap and secured to it and riveted to the side flanges of the compression member.
2. In a bolster, the combination of a channel-shaped compression member, a tension member secured thereto and extending inward horizontally from the end of the bolster and then inclining upward, and a stirrup com-

posed of a sheet-metal plate bent into a vertical U form and bifurcated on opposite sides, the intermediate portion thereof being bent at an angle to itself corresponding to the bend in the tension-strap, said stirrup being secured both to the tension-strap and the compression member.

3. In a bolster, the combination of a channel-shaped compression member, a flat tension-strap bent down at its end across the end of the compression member and there secured, a stirrup lying on the upper side of the tension-strap and extending downward along the sides of the compression member, rivets passing through the downward extensions of the stirrup and the sides of the compression member, portions of the car side resting on the upper face of the stirrup, and rivets passing through such portions, through the stirrup, through the tension-strap, and through the compression member, and securing said parts together.

In testimony whereof we hereunto affix our signatures in the presence of two witnesses.

JOHN E. LOMBARD.
JOSEPH R. BOWLING.
